GRID STRUCTURE FOR REFRIGERATORS

Gust Roud, Evansville, Ind., assignor to Servel, Inc., New York, N. Y., a corporation of Delaware

Application November 10, 1936, Serial No. 110,077

5 Claims. (Cl. 62—108.5)

1

My invention relates to grid structures for use in the production of ice cubes in refrigerators.

It is an object of my invention to provide an improved flexible grid structure which is inexpensive, readily assembled, and from which ice cubes can easily be removed by a simple bending action of the grid structure.

The invention, together with the objects and advantages thereof, will become apparent from the following description taken in conjunction with the accompanying drawing forming a part of this specification, and of which Fig. 1 is a plan view of an ice tray within which is positioned a flexible grid structure embodying my invention; Fig. 2 is a side elevation of the grid structure shown in Fig. 1; and Fig. 3 is a view similar to Fig. 2 with the flexible grid structure bent or bowed to illustrate more clearly the manner in which ice cubes are removed therefrom.

In Fig. 1, a grid structure 10 is shown positioned in an ice tray 11 which is provided with an outward extending flange 12 about the upper edges of the walls thereof. The flange 12 at one end of the tray is slightly wider and bent downward at its extreme end to provide a finger grip for the tray.

The grid structure 10 comprises a plurality of spaced transverse partitions or dividing members 14 which are substantially the same depth as the tray 11 and extend between the longitudinal side walls thereof. Between the transverse members 14 are arranged a plurality of aligned vertical longitudinal dividing members 15 which also are substantially the same depth as the tray 11. The bottom corners of the longitudinal members 15 are directly hinged or pivotally connected to the bottom edges of the transverse members 14. This may be accomplished by securing a pair of small angle members 16, as by spot welding, for example, to each face of a transverse member 14, as shown most clearly in Fig. 1. The arms of the angle members 16 extending away from the transverse members 14 are in spaced relation and are adapted to receive the bottom corners of the longitudinal members 15. The bottom corners of the longitudinal members 15 and outward extending arms of the angle members 16 are provided with openings to receive pins 17 which are fastened to the angle members 16.

A pair of levers 18 are pivotally connected to the top outer corners of the end longitudinal members 15 for removing the grid structure 10 from the tray 11 and for applying force to the grid structure to bow or flex the latter to free ice cubes therefrom. The levers 18 are pivotally con-

nected to the end longitudinal members 15 by pins 19 which extend through openings in the members 15 and forked rounded inner ends of the levers. The forked rounded inner ends of the levers 18 are so formed that, when the levers are pulled upward from the position shown in Fig. 1, the extreme outer portions 20 bear against the upper edges of the end walls of the tray to remove the grid structure from the tray.

After the grid structure 10 has been removed from the tray 11, the levers 18 can be moved to the horizontal position shown in Fig. 2 with the levers in alignment with the longitudinal members 15. The slots 21 formed at the forked inner ends of the levers 18 are such that, when the levers are moved to this position, the inner ends of the slots bear against the vertical edges of the end longitudinal members 15, whereby further downward movement of the levers causes the transverse and longitudinal members 14 and 15 to bow or arch, as shown in Fig. 3.

To permit angular movement of the transverse and longitudinal members 14 and 15 and also limit the extent to which the grid structure 10 can be bowed or arched when downward force is applied to the levers 18, the bottom corners of the longitudinal members 15 are slightly rounded, as indicated at 22 in Fig. 2. By sloping the vertical edges of the longitudinal members 15 away from the transverse members 14 at the bottom edges of these members, each longitudinal member can be angularly moved away from an adjacent transverse member a limited distance until the sloping portion 22 of the longitudinal member bears against the face of a transverse member.

In using the grid structure just described, the structure is positioned in a tray, as shown in Fig. 1, and the latter is filled with water. After the water has been frozen and ice cubes have been produced by placing the tray in a cooling unit of a refrigerator, the tray is taken out of the cooling unit and the grid structure removed from the tray in the manner described above. With the levers 18 in the horizontal position shown in Fig. 2, downward force is applied to the levers to flex or bow the grid structure, as shown in Fig. 3.

This is preferably accomplished by holding the levers 18 and simultaneously applying such downward force to the levers. The ice cubes are readily released by flexing or bowing the grid structure, the ice cubes at the ends of the structure being released first. When the downward force is first applied to the levers 18, the force is transmitted directly to the end longitudinal members 15 and causes the latter to be moved angu-

larly with respect to the adjacent transverse members 14. When the end longitudinal members 15 have been moved angularly such a distance that the sloping portions 22 bear against the faces of adjacent transverse members 14, the force applied to the levers 18 is transmitted directly to the end transverse members 14 and they are caused to be moved angularly with respect to the longitudinal members 15 adjacent to the end longitudinal members. In this manner the force applied to the levers 18 is transmitted throughout the grid structure from the ends thereof toward the center until all of the ice cubes have been released.

In flexing or bowing the grid structure, the separation of the longitudinal members 15 and transverse members 14 causes the ice cubes to peel from the transverse members, and the angular movement of the longitudinal members 15 with respect to the transverse members 14 causes the ice cubes to peel from the longitudinal members. By directly hinging the partitions or dividing members 14 and 15 adjacent the edges of said members in the bottom plane of the grid structure and having no other connection therebetween, the force applied to the operating levers 18 is effectively transmitted directly to the members to free the ice cubes therefrom. With this particular grid structure, I am able to use solid walls or dividing members whereby the cost of manufacture is reduced considerably over grid structures formed of double wall partitions. It is to be understood, however, that double wall partitions or dividing members may also be used in practicing my invention. By employing solid wall dividing members stamped from sheet metal and only using a relatively few different parts, I provide a grid structure which can be quickly and easily assembled and is inexpensive to manufacture.

Although I have shown and described a particular embodiment of my invention, it will be apparent that modifications and changes may be made without departing from the spirit and scope of my invention.

What is claimed is:

1. A flexible grid structure for refrigerators comprising a plurality of spaced transverse wall members, a plurality of aligned vertical longitudinal dividing members arranged between said transverse members, spaced arms fixed to the sides of said transverse members adapted to receive a bottom corner of said longitudinal members, said arms and bottom corners of said longitudinal members being hinged, the vertical edges of said longitudinal members adjacent the bottom corners thereof sloping away from said

transverse members to permit said transverse and longitudinal members to be moved angularly with respect to each other and to limit the extent of such angular movement.

5 2. A distortable grid for refrigerator ice freezing trays comprising a plurality of spaced transverse walls, a plurality of aligned longitudinal walls between said transverse walls, the bottom corners of said longitudinal walls being connected to the bottom edges of said transverse walls by a pivotal joint to permit angular fractures at said transverse walls upon distortion of the grid.

15 3. A distortable grid for refrigerator ice freezing trays and comprising a plurality of alternate transverse and longitudinal walls in substantially vertical intersecting planes, interconnecting hinges to permit relative movement upon exertion of a distorting force, and constructed and arranged so that said force is exerted upon a longitudinal wall through a transverse wall.

20 4. A distortable grid for refrigerator ice freezing trays comprising a plurality of spaced transverse walls in substantially upright parallel planes, a plurality of intermediate longitudinal walls in substantially the same upright plane intersecting said transverse walls, and interconnections formed by hinges on said transverse walls so that a distorting force may be applied to swing one longitudinal wall before exertion of force on the next.

25 5. A distortable grid for refrigerator ice freezing trays comprising a plurality of spaced transverse walls, a plurality of aligned longitudinal walls between said transverse walls, the longitudinal walls being connected to said transverse walls by pivotal joints to permit progressive angular fractures at said transverse walls upon distortion of the grid, and said longitudinal walls being so shaped that the angle of said fractures is predetermined.
